C. BLAMFIELD.

PISTOL LIGHT.

APPLICATION FILED MAR. 3, 1919.

1,327,585.

Patented Jan. 6, 1920.

Inventor,

Charles Blamfield;

By *A. B. Upshaw,*
Attorney.

UNITED STATES PATENT OFFICE.

CHARLES BLAMFIELD, OF BOSTON, MASSACHUSETTS.

PISTOL-LIGHT.

1,327,585.

Specification of Letters Patent.

Patented Jan. 6, 1920.

Application filed March 3, 1919. Serial No. 280,483.

To all whom it may concern:

Be it known that I, CHARLES BLAMFIELD, a subject of Great Britain, and a resident of Boston, in the county of Suffolk and 5 Commonwealth of Massachusetts, have invented certain new and useful Improvements in Pistol-Lights, of which the following is a full, clear, and exact specification.

The object of this invention is the construction of an article preferably resembling a pistol in general outline, and adapted to hold a match in a manner to be ignited when the "trigger" is pulled, both as a toy and as a means for lighting a cigar, 15 a pipe or a stove-fire; the same being also adapted to be automatically set off after a predetermined interval of time.

In the drawings forming part of this specification, Figure 1 is a side view of a 20 pistol-light embodying my improvements. Fig. 2 is an opposite side view, and with parts in a slightly different position. Fig. 3 is a plan view of the same. Fig. 4 is a perspective view of the pistol. Fig. 5 is 25 a perspective view of the front end thereof.

The reference numeral 1 designates the "body" portion and 2 the "handle" or "stock," the two parts being either integral or made 30 separate and suitably fastened together.

30 The "trigger" and "hammer" are composed of a single straight stick 3 pivoted to the body at 4 and caused to fly over into substantial alinement with the body 1 by means of a rubber band or other elastic device 5 attached to the hammer by a projecting pin 35 6, and in any suitable manner to the body at 7.

By swinging the hammer 3 over until the pin 25 contacts with the butt and the pivot 4 is slightly above the elastic 5 40 stretched between 6 and 7, the hammer remains in such position. The end now in front of the pivot 4 being cut away at an acute angle to present a trigger 10 to the forefinger of the hand clasping the handle 2, 45 it takes but a slight pull thereon to elevate the hammer 3 enough to cause the elastic to snap the hammer over to a position a little below parallelism with the body, a notch 11 being cut in the side of the body to receive 50 the pin 25.

As shown in Figs. 3 and 4, a portion of the front end of the body 1 is cut away and given a protecting shield of sheet metal 12 to protect the wooden body from ignition, 55 and transversely through both shield and wood are drilled preferably two holes 13,

14 of slightly different sizes. Through one of these holes is thrust a match until its head 15 alone projects therefrom, as shown in Fig. 3, after which the stem of the match 60 can be broken off.

To the side of the hammer-end is attached a metal striking plate 16, as shown in Fig. 5, so that when the hammer descends to its position here shown, the friction of 65 the plate along the match-tip will at once ignite the latter.

As thus far described, this is the construction and operation of the device as a toy pistol, and for lighting a cigar and the like, 70 but for starting a stove fire at a predetermined time, a further addition must be made. This consists of a cork 17 glued or otherwise fastened to the overhang 19, and a cup 20 adapted to contain a liquid and 75 to be pressed up into engagement with the cork. At the end of the cork is attached a small metal clip 21 for receiving a small block of soluble material 22, and around this block is looped a thread or wire 23 80 whose ends are fastened to the pistol at 24. Projecting from the side of the hammer 3 is a pin 25 over which the thread or wire 23 is passed to hold it in the half-cocked position shown in Fig. 2, the block of soluble 85 material 22 being in the loop of the thread or wire, and thereby retaining the hammer until such time as water or other suitable fluid is permitted to reach and dissolve the block. Then the thread or wire pulls 90 through the softened mass and the hammer falls.

I find it preferable to have the block 22 composed of sugar or other quickly soluble substance and to protect it temporarily by 95 a cylinder 26 having its otherwise open end closed by a plug 27 of more slowly soluble material composed of powdered rosin and soda. Hence, the cup 20 being more or less filled with water, the plug 27 is slowly dissolved thereby until sufficiently pervious to permit the water to reach the block 22. Then the latter quickly dissolves and the 100 thread can pull out, and the hammer strike.

As indicated in Figs. 2 and 4, the overhang 19 and the cork are somewhat slotted to permit the easy passage of the thread or wire 23.

For lighting a fire, I provide a pin or band 29 near the end of the hammer 3 for receiving a bit of prepared fabric 30, as shown in Fig. 5, saturated with an easily combust-

tible material, as wax. This may be netting or even a more attenuated fabric, but when introduced between the band 29 and the surface of the hammer it rises into position 5 to receive the effect of the flame bursting from an ignited match, and then burns until it has accomplished the desired function of kindling the wood and chips to be lighted.

The igniting plate 16 is also disposed to 10 be used for breaking away the head of a consumed match and making the way clear for the expulsion of the latter and the introduction of a fresh match, the burnt portion being pushed through the hole by the 15 end of the new match.

When the pistol is used for lighting a 20 stove fire, a pin or hook 31 is provided, as shown in Figs. 2 and 4, the pin being normally contained in the groove 32, but when 25 to be used it is pried out from this groove and swung around to a position in which it can be stuck into any suitably supporting object, or be hooked over some part of the stove or grate. Then the pistol will remain in place until its contained match has 30 been struck and the fire started.

In using the pistol light, its handle or 35 stock 2 may be held in the hand, a match inserted in the hole at the end of the body, 40 the body pulled over until in the position illustrated in Fig. 1, and then the pistol 45 "fired" by a pulling action given either by a forefinger or thumb upon the pointed end 50. The forward and downward swing of 55 the hammer carries its igniter plate 16 past the match-head to a position slightly below the level of the body, as shown in Fig. 5, at which point the hammer comes to rest upon the stop 7 whose other function is that 60 of an attachment for the elastic band 5.

The use of the pistol light for starting 65 fires at a predetermined time has already been described.

What I claim is:

45 1. A pistol light comprising a body, a hammer consisting of a straight length of material pivoted at an intermediate point to the side of the body, the body having a match-supporting device near its end for holding a match-head in the path of the hammer, and an elastically elongative member attached to the body and the hammer, the points of attachment being disposed to lie below the pivotal point of the hammer 50 when the latter is set, and thereby serving to retain it in such position until released. 55

2. A pistol light comprising a body, a hammer pivotally connected therewith, means for supporting a match in the

path of the hammer, means for supporting 60 soluble material, means for supporting a fluid for acting on said material, and a filament connected with the hammer and adapted to be held by said soluble material until dissolved, the hammer being held from action by said filament until said material is 65 dissolved.

3. A pistol light comprising a body, a hammer pivotally connected with the body, means whereby the body supports a match 70 in the path of the hammer, a cork supported by the body, a clip for holding a block of easily soluble material at the lower end of the cork, a cylindrical cup for containing a fluid adapted to be pressed into engagement 75 with the cork, and a filament connected with the hammer and soluble block to hold the hammer set until the block is dissolved, the hammer having resilient means for actuating it. 80

4. A pistol light comprising a body, a hammer pivotally connected therewith, means for supporting a match in the path of the hammer, a filament connected with the hammer, an easily soluble block holding 85 the filament and thereby the hammer from actuation, means inclosing the easily soluble block away from a surrounding fluid, this means embracing a slowly soluble barrier, and resilient means for actuating the 90 hammer.

5. A pistol light comprising a body and stock, a hammer pivoted thereto, means for supporting a match in the path of the hammer, a cork supported by the barrel, a cylindrical cup adapted to be pressed into engagement with the cork, a clip for holding a block of easily soluble material, at the end of the cork, a cylinder inclosing the clip and its contents, a soluble plug closing the 100 lower end of said cylinder, a filament connected with the hammer and with a block of soluble material in said clip, and resilient means for actuating the hammer. 105

6. A pistol light comprising a body having a transverse hole near its end, a hammer pivotally connected therewith to swing down beside the body, resilient means for actuating the hammer, and a stop for holding the hammer slightly below the body 110 end when released, said hole being designed to carry a match, and the hammer a combustible fabric.

In testimony that I claim the foregoing invention, I have hereunto set my hand this 115 27th day of February, 1919.

CHARLES BLAMFIELD.
